(57) **CLAIM**

The ornamental design for a headlamp, as shown and described.

DESCRIPTION

FIG. 1 is a front, right, top perspective view of a first embodiment of a headlamp showing my new design;

FIG. 2 is a rear, left, top perspective view thereof;

FIG. 3 is a rear, left, bottom perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof; and,

FIG. 9 is a bottom view thereof.

A second embodiment of the claimed design for the headlamp is a mirror image of the headlamp as shown in FIGS. 1 to 9.

1 Claim, 5 Drawing Sheets
